No. 36,691.

Patented December 22, 1903.

UNITED STATES PATENT OFFICE.

ERNEST OLDENBUSCH, OF BROOKLYN, NEW YORK.

DESIGN FOR A FRAME FOR PICTURES, MIRRORS, OR SIMILAR ARTICLES.

SPECIFICATION forming part of Design No. 36,691, dated December 22, 1903.

Application filed September 21, 1903. Serial No. 174,119. Term of patent 3½ years.

To all whom it may concern:

Be it known that I, ERNEST OLDENBUSCH, a citizen of the United States, and a resident of Brooklyn, in the county of Kings and State of New York, have invented a new, original, and ornamental Design for a Frame for Pictures, Mirrors, or Similar Objects, of which the following is a specification, reference being had to the accompanying drawings, forming part thereof.

My design is fully shown in the accompanying drawings, in which—

Figure 1 is a plan view of the frame, showing my new design. Fig. 2 is a cross-section of the same.

I claim—

The ornamental design for a frame for pictures, mirrors, and similar objects substantially as shown.

ERNEST OLDENBUSCH.
